UNITED STATES PATENT OFFICE.

HERBERT L. BROWN AND CLIFFORD C. WHEELER, OF NEWPORT, MAINE.

CLOTH-METER.

1,295,423.

Specification of Letters Patent. Patented Feb. 25, 1919.

Application filed July 16, 1915. Serial No. 40,324.

To all whom it may concern:

Be it known that we, HERBERT L. BROWN and CLIFFORD C. WHEELER, citizens of the United States, residing at Newport, in the 5 county of Penobscot and State of Maine, have invented certain new and useful Improvements in Cloth-Meters, of which the following is a specification.

This invention relates to the class of linear 10 measuring apparatus and is particularly concerned in the provision of a device for the automatic measuring of cloth web produced by a loom.

As a principal object, it is contemplated 15 by this invention to provide a series of dials having pointers and a separate actuating mechanism for each pointer; to provide means in contact with the cloth for actuating the first dial pointer and to subsequently 20 actuate successive dial pointers after the completion of one rotation on the part of the preceding pointer.

A further object is to provide spring 25 means for maintaining the cloth in constant engagement with a toothed roll of predetermined circumference for the actuation of the first dial pointer so that the measuring of the cloth will be automatically undertaken by the device in accordance with the 30 passage of the cloth web under the roll.

The above and additional objects which will be hereinafter more specifically treated, are accomplished by such means as are illustrated in the accompanying drawings, de- 35 scribed in the following specification and then more particularly pointed out in the claim which is appended hereto and forms a part of this application.

With reference to the drawings, wherein 40 there is illustrated the preferred embodiment of this invention as it is reduced to practice, and throughout the several views of which like characters of reference designate similar parts:—

Figure 1 is a vertical sectional view 45 through the casing mounting the measuring means of this invention;

Fig. 2 is a plan view of the same subject-matter, and

Fig. 3 is a horizontal sectional view showing the actuating mechanism for the various 50 dial pointers.

There is employed a casing 5 which may be readily clamped by some extraneous 55 means, not illustrated, to the breast beam of the loom, preferably between the breast

beam and either the right or left hand temple and has a variety of positions with respect to the loom which need be limited only by the contact with the cloth web 6 of the roll 60 7 which is mounted at the extremity of an axle 8 journaled in suitable partitions 9 forming a portion of the inclosing casing. This roll 7 is provided upon its periphery with a suitable number of fine teeth or pins 65 which are adapted to engage the cloth web 6 in positively rotating the roll in exact accordance with the passage of the cloth to be measured. A lever 10 is pivoted at 11 between its ends to an ear depending from 70 the casing 5, and has a long outer arm depending somewhat from its pivot and dished at its outer end as at 12 where it underlies the roll 7, while its inner arm is normally depressed by a spring 13 to throw its outer arm 75 upward. The purpose of dishing this arm of the lever is so that it will press the cloth reliably upward against the roll, but yet will not contact with the fine teeth on the latter because it touches the roll only at the edges 80 thereof. It is manifestly desirable that the tips of the teeth shall not be worn off, and this important detail of construction secures this end.

On the upper surface of the casing 5 there 85 are provided a number of dials respectively denoted by the numerals 14, 15 and 16 each of which is provided with a central aperture for the reception of a stem 17 which carries the pointer or indicator finger 18, 90 movement of which over the dials will indicate at all times the true length of the cloth web. The stems 17 are each journaled in the opposite side of the casing 5 and have their central portions enlarged, or as 95 an equivalent construction, provided with inclosing sleeves 19 upon which are secured the gears for operating the respective pointers.

A small pinion or spur gear 20 is carried 100 on the inner extremity of the roll shaft 8 and adapted to mesh therewith is the crown gear 21 operating the pointer for the dial 14. A stem 22 has its extremities journaled in the casing between the stem 17 of the adjacent 105 dials 14 and 15 and is provided with a plurality of arms 23 which extend over the upper surface of the crown gear in the path of travel of a pin 24 carried by the crown gear. A pinion 25 is also carried by the shaft 22 110 and is adapted to mesh directly with the large gear 26 which operates the pointer for

the dial 15. A pin 27 is also carried by this last mentioned gear in order to contact directly with the teeth of the spur gear 28 which operates the pointer for the third dial 16. A glass cover may obviously be provided to protect the dials and pointers from the dirt which is usually prevalent during the operation of the loom.

From the foregoing it will be apparent that rotation of the roll 7 is transmitted to the crown gear through the medium of the pinion 20 and that each complete rotation of the crown gear is registered by a slight movement of the next gear 26 which in turn has its own complete revolutions summed upon the third gear 28. In practice it has been found desirable to provide a roll the circumference of which measures, three inches and to also proportion the teeth of the pinion 20 and of the crown gear in the ratio of 12 to 1, so that each complete revolution of the crown gear will measure 36 inches or 1 yard, which will carry the pointer entirely around the dial 14. The pin 24 will be also moved to strike one of the arms 23 at each revolution of the crown gear which will in turn advance the pointer for the dial 15, the teeth of the gear 26 being so arranged as to necessitate 50 revolutions of the crown gear before completing one of its own revolutions. In like manner the revolutions of the gear 26 are summed upon the final gear 28, which may, however, in many embodiments of the device be dispensed with should the capacity of the loom not exceed 50 or 60 yards which can be accommodated by the first two dials. By the use of the arms 23 and gear 25 the motion of the pointers 18 for both the dials 14 and 15 is provided in the same direction and it will be apparent that a similar means may be employed between the dials 15 and

16, when the latter is made use of. If left hand reading meter be desired, owing to some restrictions or limitations of position upon the loom, it is obvious that the cloth web may pass over the toothed roll 7 instead of below the same as shown in order to effect a rotation of the pointer or pointers in the desired direction.

While in the foregoing, however, there has thus been illustrated in the drawings and described in the specification such combination and arrangement of elements as constitute the preferred embodiment of this invention, it is desired to emphasize the fact that such minor changes in the matters of proportion and degree may be made in later adaptations of this device as shall not alter the spirit of the invention as defined in the appended claim.

What is claimed is:

A cloth meter comprising a casing, a shaft journaled within and projecting beyond one end of the same, computing mechanism within the casing actuated by the rotation of said shaft, a drum on the outer end of the shaft provided with pointed teeth projecting from its periphery, a lever pivoted between its ends beneath the casing and with its outer arm depending from its pivot and dished at its outer end where it underlies the roll, and an expansive spring between its inner arm and the casing throwing said dished end normally toward the roll, the whole for use substantially as described.

In testimony whereof we affix our signatures in presence of two witnesses.

HERBERT L. BROWN.
CLIFFORD C. WHEELER.
